TOWEL BAR

Filed Dec. 9, 1924

FIG. 1.

FIG. 2.

FIG. 3.

FIG. 4.

Inventor:

EUSTACHIUS W. KOERING
By Marvin J. Reynolds
Attorney

UNITED STATES PATENT OFFICE.

EUSTACHIUS W. KOERING, OF VINELAND, NEW JERSEY.

TOWEL BAR.

Application filed December 9, 1924. Serial No. 754,705.

This invention relates to a towel bar and more particularly to a towel bar composed of glass or other vitreous material and a novel support or bracket therefor whereby the bar 5 may be suspended from a wall or other surface.

Heretofore, in the construction of towel bars, it has been the usual practice to make the bar of a straight rod of glass of suitable 10 length and to support the same by means of metal brackets extending outwardly from the wall at right angles to the bar. Such construction has serious disadvantages however, since it permits the damp towels or 15 other objects hung thereover, to come into contact with the metal bracket, causing the nickel plating to be worn off, exposing the brass base which quickly becomes corroded and unsightly. Furthermore, in such construction the bar fits more or less loosely in 20 openings in the ends of such brackets and, due to the inherent nature of the bracket, such as the necessary length thereof, the outer ends thereof often become bent away from each 25 other, unless the brackets are made unduly large or heavy, permitting a slight amount of end play or longitudinal movement of the bar and consequent rattling thereof in the brackets. Moreover, difficulty has been experienced in bars supported in accordance 30 with prior construction, by moisture and dirt accumulating in and about the opening in the bracket in which the bar is supported.

One of the objects of this invention is to 35 provide a towel bar composed of glass or other vitreous material having metal supports, in which the towels or other objects supported on the bar will normally be out of contact with the metal supports.

Another object is to provide a towel bar 40 composed of glass or other vitreous material and having relatively small metal supports or brackets.

Another object is to provide an improved 45 support for a towel bar or similar article, which is pleasing in appearance, simple in construction, inexpensive in manufacture and which will support the bar in a firm and rigid manner.

Another object is to provide a towel bar

and bracket which may be readily cleaned and in which there will be no accumulation of dirt within or about the bracket openings.

Other objects and advantages will herein-after appear.

In accordance with this invention the bar, which may be composed of glass, porcelain or other vitreous, non-corrodible and easily cleanable material has a substantial portion adjacent each end bent inwardly at right angles to the body portion of the bar and each of such inwardly turned ends is supported by a metal bracket which extends outwardly from the wall a relatively short distance. A bead or shoulder is preferably formed on each end of the glass bar and abuts against the end of the opening in the bracket in which the bar extends. The extreme ends of the bars are grooved for engagement by a spring clip which serves to retain the end of the bar centered in the bracket and to hold the bead or enlargement on the bar tightly against the outer end of the bracket. Obviously other means may be provided for retaining the rod within the bracket, without departing from the scope of this invention.

In order that the invention may be more fully understood, reference will be had to the accompanying drawings, in which,

Fig. 1 is an elevation, partly in section of 80 the towel rack applied to a wall;

Fig. 2 is an exterior view of the bracket;

Fig. 3 is a plan of the spring member for retaining the bar within the bracket; and

Fig. 4 is a plan of the bracket and a portion of the bar secured therein.

This invention in the embodiment shown in Figure 1, comprises a bar 1 of glass or other vitreous material, having inwardly turned ends 2 and 3 engaging in and supported by a pair of spaced brackets 4 and 5. Each of the brackets 4 and 5 is composed of a hollow metal shell 6, preferably of nickel plated brass, and a concave spring retaining member 7 of spring steel. The shell 6 is, generally speaking, of flaring conical shape, and the base 8 thereof has an annular flange 9 therearound, to form a recess 10 in the underside of the shell in which the spring retaining member 7 is received.

The rod or bar 1 has an annular bead or shoulder 11 formed on each of the inwardly turned ends 2 and 3, which seats against the outer edge 12 of the bracket and is held tightly thereagainst by the spring retaining member 7, as will hereinafter appear, whereby the entrance of dirt and moisture into the interior of the bracket around the bar is precluded.

10 The retaining member 7, preferably is in the form of a dished or concave spider and is composed of a resilient metal, such as spring steel. A slot 13 communicating with the central opening 14 permits the retaining member 15 to be slid over the groove 15 formed on the end of the bar 1. The central opening 14 is slotted back on one side for a short distance, as at 16, to permit the member 7 to be sprung onto the end of the bar and to firmly engage 20 the sides of the groove 15.

25 Preferably, perforations 17 are provided in the bracket or support to permit the same to be secured to the wall by means of screws 18 or equivalent fastening means and the retaining members 7 have a plurality of radial projections 19 which extend into the recess 10 and between which the screws 18 pass.

In assembling the towel bar for attachment to a wall, the inturned ends of the bar 1 are 30 passed through the small ends of the brackets 4 and 5 and the retaining members 7 slipped thereon so as to engage in the grooves 15. The retaining members should preferably be positioned on the end of the bar so that the slot or slideway 13 will extend in a 35 substantially horizontal direction when the brackets are attached to the wall, whereby there is no tendency of the bar having a lateral movement therein.

40 The retaining member 7, it will be noted holds the end of the bar centered in the bracket and retains the bead or shoulder 11 firmly in engagement with the end of the bracket, thus producing a firm, rigid structure in which all play and looseness is eliminated. Moreover, since the bracket extends 45 only a short distance from the wall there is only slight opportunity of damp towels coming in contact therewith to wear away the nickel plating and render the support unsightly.

50 It should be further noted that the bracket is composed entirely of two pieces of stamped metal, that there are no clamped or soldered joints and that the exposed surface of the bracket is relatively small, thus effecting a substantial decrease in the cost of production thereof.

55 The bead 11 prevents moisture gathered on 60 the bar from creeping along the same and into the opening of the bracket, and since a tight contact is maintained between the bead and the end 12 of the bracket, there is no opportunity of dirt accumulating in or around 65 the end of the bracket.

While I have shown and described but a single embodiment of the invention herein, it is to be understood that the same is susceptible of different modifications and that many variations and changes may be made therein 70 without departing from the spirit of the invention.

What I claim is:

1. A support for towels and similar objects, comprising a bar of glass or other vitreous material, and a pair of brackets therefor, said bar having a circumferential groove adjacent each end and an enlargement on each end spaced from said groove, said enlargement being adapted to abut against 75 the end of the bracket and a spring retaining member within the bracket engaging said groove and uniting the bar and bracket.

2. A support for towels and similar objects, comprising a bar having its opposite 80 ends bent at an angle to the intermediate portion thereof, a circumferential groove in the bar adjacent each end thereof, an enlargement on said bar spaced from said groove, 85 a bracket surrounding each of the ends of the bar with the enlargements on the bar abutting against the outer ends of the brackets, a recess in the base of each of the brackets and a spring clip, contained in said recess engaging 90 each of said grooves for firmly locking 95 the bar and brackets together.

3. A support for towels and similar objects, comprising a bar of vitreous material, a bracket for securing the same to a wall or other surface having an annular recess therein and means for rigidly uniting said bar and bracket, said means comprising a circumferential groove formed in the bar and an abutment spaced at different distances, 100 respectively, from the end of the bar, said abutment engaging the outer end of the bracket and said groove being engaged by a spring clip contained within said annular recess.

4. A support for towels and similar objects, comprising a bar having one end thereof disposed normal to the surface from which it is to be supported, a bracket concentric with said end, an enlargement on said bar abutting against the end of the bracket and a detachable resilient retaining member within the bracket at least partially surrounding 110 the end of said bar at a distance from said enlargement to maintain the bar normal to said surface and prevent longitudinal movement thereof.

5. A support for towels and similar objects, comprising a bar having one end thereof disposed at an angle to the surface from which it is to be supported, a bracket concentric with said end, an annular recess in 115 the base of said bracket, an enlargement on said bar abutting against the end of the bracket and a retaining member within the bracket at least partially surrounding the end of said bar at a distance from said end.

largement to maintain the bar at a definite angle to said surface and prevent longitudinal movement thereof.

6. A towel bar comprising a rod having 5 its end portion provided with a circumferential groove, a bracket enclosing said end portion and engaging said rod at a point spaced outwardly from said groove, a recess

in the base of said bracket and a retaining member held within said recess and engaging 10 in said circumferential groove.

In testimony whereof, I have hereunto subscribed my name this 24th day of November, 1924.

EUSTACHIUS W. KOERING.
